CLAIM

The ornamental design for a drug container holder, as shown and described.

DESCRIPTION

FIG. 1 is a top, side and distal end perspective view of a drug container holder showing our new design;

FIG. 2 is a distal end view;

FIG. 3 is a proximal end view;

FIG. 4 is a top plan view having a bottom plan view being a mirror image; and,

FIG. 5 is a left side elevational view having a right side view being a mirror image.
